(57) CLAIM

We claim the ornamental design for a knee pad, as shown and described.

DESCRIPTION

FIG. 1 is a perspective view of a knee pad in accordance with the new design, as worn by an infant (shown in phantom).

FIG. 2 is a front elevational view of the knee pad of FIG. 1; and,

FIG. 3 is a side elevational view of the knee pad of FIG. 1. The dashed lines are for illustrative purposes only and form no part of the claimed design.
